United States Patent Office

Des. 197,148
Patented Dec. 17, 1963

197,148

BOX

Carol Parker, 1049 Mill Hill Road, Southport, Conn.

Filed Dec. 7, 1962, Ser. No. 72,767

Term of patent 7 years

(Cl. D58—12.6)

Fig. 1

Fig. 2

Fig. 3

I claim:

The ornamental design for a box, substantially as shown and described.
